UNITED STATES PATENT OFFICE

STANLEY ANTHONY, OF BOSTON, MASSACHUSETTS

FILE

Application filed August 2, 1928. Serial No. 297,067.

This invention relates to paper files of the class in which the sheets are detachably supported on sheet carriers, which in turn are detachably supported on the frame, and in which the sheets are arranged in overlapping relationship.

The invention will be best understood by reference to the following description, when taken in connection with the accompanying drawings of one specific embodiment thereof, while its scope will be more particularly pointed out in the appended claims.

In the drawings:

Fig. 1 is a front elevation of a portion of a file exemplifying the invention;

Fig. 2 is an elevation of one of the sheet carriers and the sheets carried thereby removed from the file, and with one of the sheets lifted from another and swung backward;

Fig. 3 is an elevation of one of the sheet carriers, with the normally folded sheets thereon unfolded;

Fig. 4 is a sectional view on line 4—4 of Fig. 3;

Fig. 5 is a sectional view similar to Fig. 4, but illustrating the first step in the removal of the sheet from the carrier;

Fig. 6 is another sectional view similar to Fig. 4, but illustrating the second step in the removal of the sheet from the carrier;

Fig. 7 is a perspective view, on an enlarged scale, of one of the sockets which receive the sheet carriers;

Fig. 8 is a sectional view, on an enlarged scale, on line 8—8 of Fig. 1; and

Fig. 9 is a sectional view, on an enlarged scale, on line 9—9 of Fig. 1.

Referring to the drawings, and to the embodiment of the invention which is illustrated therein, and having reference at first to Fig. 1, there is shown a file comprising a series of sheets 15, each of which in the present example is folded as at 16 (see Fig. 3). In the present example, the sheets are of comparatively light weight stock, and two identical sheets are nested together,—that is to say, one folded sheet is received within the fold of another identical sheet. In Fig. 3, one of these sheets is turned back at one corner to expose the underlying sheet. One or more sheets of this

kind, as desired, may be supported on each of the sheet carriers now to be described.

Each sheet, or group of sheets, is carried by an elongated sheet carrier, herein a flat, resilient, metallic bar 17, with which the sheet has interlocking engagement; in other words, the sheet and the carrier have interlocking means normally preventing separation of one from the other by bodily movement. In the present example, such interlocking means (see Fig. 4) are in the form of one or more pairs of oppositely directed locking projections 18 on the carrier, and complementary openings 19 in the sheet. Each projection comprises a body 20 and a tongue 21, the latter extending lengthwise of the carrier, and the outer ends of the tongues of each pair of projections preferably extending toward each other. In this instance, the projections are formed on one of the longitudinal edges of the carrier. Normally the openings 19 are elongated lengthwise of the carrier, and they are of sufficient length to permit the projections 18 to be withdrawn therefrom, when the projections are brought into proper registration therewith. The tongues 21 extend beyond the respective openings in which the projections are received, and overlie the sheet, thereby locking the sheet to the carrier. The lengths of the openings 19 and their relative arrangement are such that, by proper manipulation of the sheet and the carrier, the openings can be brought into registration with the projections, and the latter then removed from the former.

This operation is illustrated in its first step by Fig. 5, which shows the sheet as it appears after a portion of it has been moved lengthwise of the carrier, to bring one of the openings 19 into proper registration with one of the projections 18, to permit that portion of the sheet then to be moved transversely of the carrier, to disengage that part of the sheet from the carrier. During this operation, of course, the projection will pass through the opening. The next step in the operation is illustrated in Fig. 6, which shows the sheet shifted bodily lengthwise of the carrier, to bring the other opening 19 into registration

with the other projection 18, whereupon the latter may be caused to pass through the former in a direction transversely of the carrier, thereby to separate the sheet and the carrier.

5 The foregoing description is of the carrier and the sheet in their simplest form, but when desired for purposes which will presently appear, there may be, and there are 10 herein, provided additional carrier projections and sheet openings. One purpose which will be served by the employment of these is the offsetting of the sheets lengthwise of their respective carriers, so that by 15 offsetting one or more sheets with relation to the remainder, by their offset position they are distinguished. Another purpose to be served by additional projections is the attachment thereto of auxiliary sheet carriers, 20 which carry auxiliary sheets.

In the embodiment shown, the carrier is provided with additional projections which, for convenience, will be designated 18^a, 18^b and 18^c, and their characteristics are similar 25 to those of the projectons 18. The sheet is provided with additional openings which, for convenience, are designated 19^a, 19^b and 19^c.

Referring now to Fig. 2, the right-hand projection 18 and the projection 18^c afford 30 pivotal support for auxiliary sheet carriers 22, which carry an auxiliary sheet 23, herein of relatively thicker stock than the sheets 15. Each of these auxiliary sheet carriers is, in effect, a hinge piece which, as shown 35 in Fig. 9, has two arms 24 and 24', between which the sheet is received, the arm 24' being provided with one or more, herein a pair of lugs 25, received in perforations 26 provided in the sheet. The sheet is conveniently removed with its hinge pieces from 40 the main carrier, by bending or buckling the sheet to reduce its length, thereby to withdraw one of the hinge pieces from its pivot, after which the other hinge piece may be 45 withdrawn from the second pivot.

This auxiliary sheet may be offset from the position shown in Fig. 2 by shifting it to the right and attaching it to the projections 18^a and 18^b. Similarly one or more of the sheets 50 15 may be offset by first removing them from their carrier, then shifting them to the right, and finally re-attaching them to the carrier so that, reading from left to right in Fig. 6 for example, openings 19^c, 19^b, 19^a and 19 55 respectively receive and lock with projections 18^c, 18^b, 18^a and 18^a. It should be understood, of course, that before this shifting can be accomplished, the auxiliary sheet 23 must first be dismounted, and after the shifting 60 has taken place, the auxiliary sheet can be restored to the main carrier, and it can be placed in either of the two described positions on the carrier. Thus it is apparent that the sheets and the carriers are suscep- 65 tible of a considerable variation in relative

arrangements, by the simple provision of a sufficient number of projections on the carrier and corresponding openings in the sheet. Also, it is to be remembered that there may be more than one of the sheets 15 on each carrier, and that accordingly, one of these may be offset with relation to the other on its carrier.

Each of the sheet carriers 17 has reduced terminal portions 27, received in sockets (see 70 Figs. 7 and 8), there being a series of pairs of these sockets supported by an appropriate support, herein a plate of sheet metal bent to form a back 28, two side walls 29 and two front flanges 30, forming a pair of channels 31, in which the sockets are received. In the present example, each socket has spring means, herein a tongue 32, pressing against the inner surface of the front flange 30, and resisting movement of the socket in the channel. Herein, the socket is conveniently made of a piece of sheet metal bent to provide four walls, one of which is the spring tongue 32, another a side wall 33, another a back wall 34, and another a wall 35, which is 80 provided with an aperture 36, in which the terminal portion 27 of the sheet carrier is received. The shape and dimensions of the aperture and of the end of the carrier are such that the latter is capable of turning movement with relation to the socket. The width of the aperture 36 (i. e., lengthwise of the channels) is only slightly greater than the width of the terminal portion 27, as a result of which accurate spacing of the overlapping margins of the sheet is maintained. The other dimension of the aperture is such that free turning movement of the carrier, as well as in-and-out movement relatively to the back of the frame, are permitted. As a result, the sheets will normally lie flat in 90 place, but may be turned from a depending position to an upstanding position,—that is to say, through an angle of substantially 180 degrees.

In this embodiment, the flange 30 slopes inwardly toward the back wall 28 of the frame, and the wall 35 projects outwardly beyond the free edge of the flange, but not beyond that part of the flange which adjoins the side wall 29. Thus, while the extremity of the wall 35 is rendered accessible for engagement by the finger, to withdraw the socket from the channel, yet the extremity of the wall does not present an obstruction, and does not increase the front-to-back thickness of the file. Herein, the shape and relationship of the spring tongue 32 to the flange 30 are such that the tongue yields and springs rearwardly when sufficient force is 100 applied to the projecting portion of the wall 35 to force the socket out of the channel, the spring tongue yielding rearwardly as it passes behind the edge of the flange.

As already intimated, the cards 23 may be 105

omitted if desired. On the other hand, when the cards 23 are used, the folded sheets 15 may be omitted. When both sets are used, the full capacity of the file is obtained. Herein, the sheets 15 are provided with apertures 37 (see Fig. 3), along the line of the fold 16, to give them greater flexibility at this point.

Having thus described one embodiment of the invention, but without limiting myself thereto, what I claim and desire by Letters Patent to secure is:

1. In a file, the combination of an elongated sheet carrier provided with two locking projections, each having a tongue extending toward the other, and a sheet provided with two openings which receive said projections and are elongated lengthwise of said carrier, said tongues extending beyond the respective openings in which they are received and overlying said sheet thereby to lock said sheet to said carrier, the distance between said openings being greater than the distance between the tongue ends and the lengths of said openings being sufficient to permit said openings to be brought into registration with said projections upon flexing the sheet, whereby the sheet may be removed from the carrier.

2. In a file, the combination of a sheet carrier comprising a bar provided with two projections, each having a tongue extending toward the other, and a sheet provided with two openings which receive said projections, respectively, and are of sufficient length to permit said projections, when brought into registration therewith by flexing the sheet, to pass therethrough by movement perpendicular to said bar, the distance between said openings being greater than the distance between the tongue ends and said tongues upon straightening of the sheet extending beyond their respective openings and overlying said sheet.

3. In a file, the combination of a sheet carrier comprising a flat bar provided with two projections on one edge, each projection having a tongue extending toward the other, and a sheet provided with two openings which receive said projections, respectively, and are of sufficient length to permit said projections, when brought into registration therewith by flexing the sheet, to pass therethrough by movement perpendicular to said bar, the distance between said openings being greater than the distance between the tongue ends and said tongues upon straightening of the sheet extending beyond their respective openings and overlying said sheet.

4. In a file, the combination of a sheet carrier provided with two projections, each having a tongue extending toward the other, and a folded sheet provided adjacent its fold with two openings which receive said projections, respectively, and are of sufficient length to permit said projections, when brought into registration therewith by flexing the sheet to

pass therethrough by movement perpendicular to said carrier, the distance between said openings being greater than the distance between the tongue ends and said tongues upon straightening of the sheet extending beyond their respective openings and overlying said sheet.

5. In a file, the combination of a sheet carrier provided with two projections, each having a tongue extending toward the other, and a folded sheet which receives said carrier within its fold, said sheet being provided adjacent its fold with two openings which receive said projections, respectively, and are of sufficient length to permit said projections, when brought into registration therewith by flexing the sheet, to pass therethrough by movement perpendicular to said carrier, the distance between said openings being greater than the distance between the tongue ends and said tongues upon straightening of the sheet extending beyond their respective openings and overlying said sheet.

6. In a file, the combination of a flat sheet carrier provided with two projections, each having a tongue extending toward the other, and a folded sheet which receives said carrier flatwise within its fold, said sheet being provided adjacent its fold with two openings which receive said projections, respectively, and are of sufficient length to permit said projections, when brought into registration therewith by flexing the sheet, to pass therethrough by movement perpendicular to said carrier, the distance between said openings being greater than the distance between the tongue ends and said tongues upon straightening of the sheet extending beyond their respective openings and overlying said sheet.

7. In a file, the combination of a sheet carrier provided with two projections, each comprising a body and a tongue, the free ends of said tongues extending toward each other, a folded sheet which receives said carrier in its fold and which is provided adjacent its fold with openings in which said projections are received, auxiliary sheet carriers mounted on said projections, respectively, and an auxiliary sheet carried by said auxiliary sheet carriers.

8. In a file, the combination of a main sheet carrier comprising a flat bar having on one edge a plurality of tongues comprising two pairs, the free ends of the tongues of each pair being directed toward each other, auxiliary sheet carriers mounted on the tongues of one pair, and a sheet carried by said auxiliary sheet carriers, said auxiliary sheet carriers, with the sheet carried thereby, being shiftable to occupy the tongues of the other pair and offset the sheet from its former position.

9. In a file, the combination of a main sheet carrier comprising a flat bar having on one edge two projections having tongues

whose free ends are directed toward each other, a folded sheet mounted on and receiving said carrier within its fold and provided with perforations through which said projections extend, auxiliary sheet carriers mounted on said tongues, respectively, and an auxiliary sheet carried by said auxiliary sheet carriers.

10. In a file, the combination of an elongated sheet carrier provided with two projections, each comprising a body and a tongue extending lengthwise of said carrier, the free ends of said tongues extending toward each other, and a sheet provided with two openings elongated lengthwise of said carrier and receiving the bodies of said projections, respectively, the length of each opening being at least as great as the length of the body and neck of the projection which it receives, the tongue of such projection extending beyond such opening and overlying said sheet, the tongue of the second projection extending beyond its opening and overlying said sheet, said projections being spaced apart a sufficient distance to permit said sheet to be bent to withdraw it from beneath the overlying tongue of the second projection and to withdraw said second projection from the opening in which it is received, thereby to permit said sheet to be shifted lengthwise of said carrier until the first perforation registers with the total length of the first projection and thus to permit said sheet to be detached from said carrier by withdrawing the first projection through the first perforation.

11. In a file, the combination of an elongated sheet carrier provided with two projections, each comprising a body and a tongue extending lengthwise of said carrier, the free ends of said tongues extending toward each other, and a sheet provided with a perforation elongated lengthwise of said carrier and receiving the body of one of said projections, the length of said perforation being at least as great as the length of the body of such projection plus the length of its neck, the tongue of such projection extending beyond said perforation and overlying said sheet, the tongue of the other projection overlying said sheet, said projections being spaced apart a sufficient distance to permit said sheet to be bent to withdraw it from beneath the overlying tongue of the second projection, thereby to permit said sheet to be shifted lengthwise of said carrier until said perforation registers with the total length of the first projection and thus to permit said sheet to be detached from said carrier by withdrawing the first projection through said perforation.

12. In a file, the combination of a rigid sheet carrier provided with spaced projecting tongues, the free ends of the tongues extending toward each other over the edge of

the carrier, and a flexible sheet folded over the carrier and having slots adapted to receive the tongues whereby the fold line of the sheet rests upon said carrier edge, the distance between the slots being greater than the distance between the tongue ends, so that the sheet may be applied to the carrier by flexing it transversely to bring the slots into registration with the tongues and so that, when applied, the tongue ends overhang the fold of the sheet and secure the sheet to the carrier.

13. In a file, the combination of a sheet carrier having a plurality of tongues arranged in pairs, the tongues of each pair extending in opposite directions and the tongues of one pair being spaced substantially the same distance as the tongues of a second pair, a sheet having openings adapted to receive and interlock with either pair of tongues, whereby the relative longitudinal position of the sheet with respect to the carrier may be varied.

14. In a file, the combination of a sheet carrier having a plurality of tongues arranged in pairs, the tongues of each pair extending toward each other over the edge of the carrier and the tongues of one pair being spaced substantially the same distance as the tongues of a second pair, a plurality of similar sheets each provided with spaced openings adapted to receive the tongues of either pair upon flexing the sheet and to interlock with said tongues when the sheet is flattened, one of said sheets being mounted on each pair of tongues whereby said sheets are offset longitudinally from each other.

In testimony whereof, I have signed my name to this specification.

STANLEY ANTHONY.
